UNITED STATES PATENT OFFICE.

WILLIAM H. WRIGHT, OF MILWAUKEE, WISCONSIN, ASSIGNOR TO FOUNDATION OVEN CORPORATION, A CORPORATION OF NEW YORK.

COKE OVEN.

Application filed June 7, 1921. Serial No. 475,633.

My invention provides a coke oven and a method of operating coke ovens by which a very uniform distribution of heat may be secured with a simple construction and arrangement of flues, and by which other advantages referred to hereinafter in detail are obtained.

The accompanying drawings illustrate an embodiment of my invention.

10 Fig. 1 is a longitudinal section through one of the flue walls on the line 1—1, Fig. 2;

Fig. 2 is a series of horizontal sections on the lines A—A (Fig. 3) and B—B, C—C, D—D and E—E (Fig. 1);

15 Fig. 3 is a longitudinal section through one of the coking chambers, on the line 3—3, Fig. 2;

20 Figs. 4 and 5 are cross-sections respectively on the correspondingly numbered lines of Fig. 2;

Fig. 6 is a diagrammatic horizontal section showing the longitudinal flues below the coking chambers, and the vertical combustion flues in the longitudinal walls between the coking chambers.

Referring to the embodiment of the invention illustrated, the oven is built on a foundation or base A of concrete, with exhaust flues B at the sides connected at intervals to the regenerators through ports C. Valves D are provided and adapted to be set either in position to admit air to the ports C and cut the latter off from communication with the main flues B, or to cut off the air and open communication with the exhaust flues; a separate valve D being provided for each regenerator along the length of the oven. The regenerator chambers on opposite sides are divided from each other by partition walls C'. At the upper outer end of each regenerator is a port E leading to a longitudinal flue F from which ports G at intervals communicate with the combustion flues in the walls between the coking chambers H. Such longitudinal flues F with ports at intervals in their length are denominated sole flues, or bus or manifold flues. The two sole flues F under an oven are cut off from each other through an intermediate wall F' (Fig. 3), but it will be understood that the coking chamber H above extends continuously from one side of the oven to the other.

Each coking chamber H is wider at one end, the right hand end in Fig. 2, so as to 55 permit the pushing of the coke out at this end, this being called the coke side of the oven and the other the pusher side.

Each regenerator chamber is divided by a horizontal wall J between two bodies of 60 brick checkerwork K and L, with a passage across the inner end of the wall J, so that the incoming air passes circuitously back and forth through the checkerwork as indicated by the arrow in Fig. 3, and the outgoing gases pass through the same path in reverse direction. The partition J is supported on projecting shelves M, Fig. 4, from the side walls of the regenerators, and the top N of the regenerator is similarly supported.

Vertical combustion flues O and P are arranged in pairs (or it may be in groups of more than two) in the flue walls Q between the successive coking chambers, the flues of 75 each pair connected to each other at the top and communicating at their lower ends with alternate sole flues. Under the flue walls and parallel with the sole flues F are gas flues R and S connected at their outer ends through suitable reversing valves with gas mains R', Fig. 1, at the sides of the oven. The gas flue R has ports leading upward into the bottom of alternate combustion flues, O, for example; and the gas flue S has 85 similar ports leading to the remaining combustion flues P. In Fig. 6 the gas ports in the bottoms of the flues are indicated by circles and the air and waste gas flues are indicated by rectangles.

90 In the roof of the furnace there are vertical passages T and U in line with the combustion flues to permit access to them for observation, for changing the gas nozzles, etc.

At the upper ends of each pair of flues O 95 and P they communicate with each other through an opening V in the wall between them.

The ports or passages G which lead from the sole flues F are alternately spaced at 100 opposite sides. See for example, the middle sole flue F in Fig. 6, with ports G on the one side communicating with combustion flues O in the flue wall at that side and with ports G on the opposite side communicating with 105 combustion flues P of the adjacent wall.

With this arrangement air comes into the central flue, Fig. 6, enters the combustion flues O at the upper side (of the figure) is mixed with gas and burns, the flue gas passing from the top of the flues O to the flues P, down the latter and out into the adjacent sole flue F; while air from the same central sole flue F passes into the combustion flue P of the flue wall on the lower side (Fig. 6) 10 mixes with gas and is burned and passes from the tops of the flues P into and down the adjacent flues O and thence out by the sole flue F at the bottom of this figure. The gas reversing valves will be shifted when 15 the air reversing valves are shifted; whereupon the two outer sole flues F of Fig. 6 will supply fresh air to the combustion flues in the two flue walls illustrated and the combustion gas will pass out through the central flue F; it being understood that the two outer flues F are supplying air also to the combustion flues in the walls at their outer sides. The incoming air passes through a heated regenerator before being admitted to 20 the sole flue F, and the combustion gas passes on reversal, from the sole flue through the same end into the regenerator.

A uniform heating of the charge from end to end of a coking chamber is of great importance for the production of a uniformly good coke and also for economy of gas. For a uniform distribution of heat along a flue wall there must be a uniform volume of air supplied to the successive combustion flues 30 along the length of the wall. In sole flues, such as are illustrated at F, the static pressure is greatest at the end remote from the entrance of air, so that to get a uniform distribution it has been proposed to provide 35 a slide brick or valve for each group of combustion flues, and to decrease by this means the effective cross-section of the successive flues or groups progressively toward the inner end of the line; or ports of fixed size 40 have been used similarly graduated.

I have discovered that the variation in the size of ports or in the effective cross-section of the passages leading through the combustion flues along the line of a sole flue 50 is not only unnecessary but also harmful in that it causes an unequal distribution of heat, and for this reason. Assuming air admitted at the right hand end of the sole flue F shown at the right of Fig. 3, its static pressure will be gradually increased until at its inner end the pressure will be a maximum. If this were the only consideration it would be necessary to correspondingly decrease the 55 size of the openings G toward the inner end 60 of the sole flue. The low static pressure at the admission end of the sole flue is accompanied by a comparatively high velocity pressure, and correspondingly at the remote end 65 of the sole flue there will be a high static pressure where the velocity pressure is lowest.

Now, if we consider each of the adjacent flues which is taking off the combustion gas produced by the air from the supply flue, the conditions will be reversed. In each of these exhaust flues there will be a comparatively low velocity pressure at the end remote from its opening into the regenerator, gradually increasing toward the exit end; and a comparatively high static pressure at the remote end gradually diminishing toward the exit. Along the exhaust flues, therefore, the velocity pressure will vary inversely with the static pressure along the admission flue; and at all points in the length of the adjacent flues there will be a counterbalancing of the pressures which will result in a substantially uniform flow of air and of combustion gas throughout the length of the line of combustion flues in question. The algebraic sum of the tendency of the air to enter a combustion flue and of the tendency of the gas to pass out of it is substantially the same for all combustion flues or separate groups of such flues along the line of a sole flue, assuming the cross-sectional area of the several ports and combustion flues to be the same.

Besides the varying pressure from end to end of each sole flue, there is a variation in the width of each coking chamber from end to end, which necessitates some special provision for securing a greater supply of heat, and a greater quantity of air, in the ends of the flue walls on the coke side of the oven, where the coking chambers are widest. There is, moreover, a uniform graduation of heat required from the wide end to the narrow end. In applying my invention, therefore, the ports leading out of the sole flues are graduated in size, not as in previous cases by making them gradually smaller from the entrance end of the sole flue to its remote end, but by making them largest at the side adjacent to the wide portions of the coking chambers and gradually diminishing 100 in size to the opposite side of the oven. In Fig. 3, for example, are shown two sole flues F in line with, but operatively separate from each other, both underlying a single coking chamber H. This chamber being wider at the right hand end, the ports G leading from the sole flues are widest at the right hand side, which is the admission end of the right hand sole flue, are gradually reduced in size to the remote or inner end of this right hand sole flue; and for the left hand sole flue F the ports commence at the right slightly smaller and gradually diminish in size toward the admission end (except for end ports G' and G² referred to specially hereinafter). This takes care of the proper distribution of heat to compensate for variation in the width of the coking chamber; and the complementary or balancing effect referred to above takes care of the variations in pres- 115 120 125 130

sure along the sole flue. This rule of gradual diminution of the ports from the coke side of the oven to the pusher side is supplemented in case of the end ports at either side of the oven, marked G' and G² respectively, by the fact that the corresponding combustion flues require an additional amount of heat to compensate for the radiation of the adjacent sides of the oven.

These ports, therefore, are made each somewhat larger than the sizes necessary to compensate for the width of the chamber, say about twenty percent (20%) larger for each port G' and G².

The system described in connection with Fig. 3 is repeated along each of the successive flue walls so that for each pair of sole flues F in line with each other there are ports G of corresponding size in the adjacent sole flues which serve to take off the combustion gas produced by the air admitted from the sole flues in question.

The principle of distribution described applies particularly to the type of combustion flues illustrated, known as the hair pin type; and to similar arrangements in which the combustion flues are in pairs or groups, each pair or group communicating with the admission and exhaust sole flues independently of the other pairs or groups. Where all the combustion flues in one side of a wall, that is in the coke side or the pusher side of the wall, are first fed by a sole flue and then discharge into a common upper bus flue, which in turn discharges into an upper bus flue at the opposite side of the combustion wall or in the same side of an adjacent combustion wall, the law of compensation referred to above is not applicable. Considering the sole flue and the bus flue corresponding to the combustion flues in one side of a wall, acting as the admission half of the circuit, these will be counterbalanced according to the law stated. In the corresponding group of outgoing bus flue, combustion flues and sole flue the openings from the bus flue and into the sole flue should be graduated in the reverse direction, but, under these circumstances, when the flow is reversed the openings from the new admission sole flue and into the corresponding bus flue will be increased in size toward the inner ends of these flues, which will be the exact reverse of the graduation necessary to compensate for the accumulation of the static pressure toward the inner end of the admission flue. Ovens built on this plan have, therefore, to adopt a compromise in the graduation of the ports which is neither the best for admission nor the best for exhaust.

The gas ports along the line will be graduated as usual to take care of variations in the temperature of the gas as the latter passes from the main gradually through the gas flue. They should also be graduated in

proportion to the width of the coking chamber and to the graduated quantities of air admitted along the flue wall from the wide to the narrow end. This control of the gas supply to the several flues may be taken care of by the application of nozzles of different sizes to the gas ports leading into the combustion flues.

I have found that with such an arrangement of valveless combustion flues along the line of each heating wall and with openings from the sole flues regulated in size not to their distance from the end of the flue, but to correspond with the width of the coking chamber, using identical sole flues for entrance and exit, a very uniform heating effect is secured throughout the length of each coking chamber. The sole flues, acting alternately as admission and exhaust sole flues, compensate for the effect of the distance of the ports from the sole flue inlets, automatically bringing about a perfect distribution of the heating air and combustion gas. It is thus possible to graduate the size of such ports from end to end of the entire heating chamber relative to the heating load adjacent each flue due to the taper in the width of the coking chamber.

The two regenerator chambers in line with each other under each coking chamber, as in Fig. 3, act in the same direction. That is, each of them passes air in the direction of the arrows shown during one period, and each of them passes combustion gas, in the opposite direction from the arrows, when the oven is reversed. These two regenerators together, therefore, carry air or combustion gas to or from half the vertical flues in the two heating walls of the coking chamber immediately above. These two regenerator chambers in line with each other and the two sole flues F above them in line with each other are in effect one regenerator and one sole flue for the coking chamber immediately above; and while the flow is in one direction through this two-part regenerator and two-part sole flue, it is in the opposite direction in the corresponding sole flues and regenerators adjacent to the one in question. By arranging the flow in the same direction (that is, outgoing or ingoing) in the regenerator chambers which are in line with each other no particular care is necessary to secure tight partitions C' or F' since there is no objection to the escape of a small quantity of air or of exhaust gases from one to the other. In fact, these partitions serve principally the function of baffles to control the currents of air and gas.

The division of each regenerator compartment into an upper and lower section provides a long travel for the air or waste heat. The checkers are laid up so that the passages run continuously from end to end to each section, which results in a lower pres-

sure drop than with staggered checkerwork. This type of regenerator chamber with the horizontal baffle J causing a circuitous and comparatively long travel for the air or 5 waste heat with its air exit at one end of the chamber is important in connection with the type of sole flue illustrated, to provide for complete and efficient utilization of the regenerative material.

10. It will be apparent that instead of securing the desired distribution of heat by making the ports G leading from the sole flues of fixed sizes, varying from one end to the other of the coking chamber, the same result 15 can be secured by the use of valves or slide bricks or other means at points between the sole flues, setting said regulating means so as to make the effective areas of the passages between the sole flues correspond with the 20 differences in width of the coking chamber from end to end. Such a regulation of the effective areas of communication between the sole flues at different points in their length has not heretofore been known; the 25 valves in use having been set in accordance with their distances from the open end of the sole flue, so that for example in the construction of Fig. 3 the effective areas would be varied progressively from the center toward the ends of the coking chamber, instead of progressively from one end to the other in the coking chamber, as in my invention. By my method of operation, therefore, I may secure the same advantages 30 from the old constructions of oven as if the ports leading directly from the sole flues were properly varied in size.

Though I have described with great particularity of detail certain embodiments of 40 my invention, yet it is not to be understood therefrom that the invention is restricted to the particular embodiments disclosed. Various modifications thereof may be made by those skilled in the art without departing 45 from the invention as defined in the following claims.

What I claim is—

1. A coke oven having coking chambers which are wider at one side than at the other 50 side of the oven with flue walls between them and having in each flue wall a line of combustion flues arranged in groups and having for each flue wall a pair of regenerators and a pair of sole flues with ports communicating with said combustion flues for supplying air to and taking combustion gas from said combustion flues at intervals along the length of each of the sole flues, each 55 group communicating with the corresponding pair of sole flues by ports which are independent of the ports from the other groups to the same sole flues, each of said sole flues having at one end a single opening adapted to be used alternately for exhaustion of combustion gas and, on reversal of 60

the oven, for admission of air, the effective areas of the passages from the sole flues through said ports and the combustion flues along each flue wall being graduated in size continuously from one side of the oven to the other, the greater areas being at the same side of the oven as the wider portion of the coking chambers.

2. A coke oven having coking chambers with flue walls between them and having in each flue wall a line of combustion flues and having sole flues for supplying air to and taking combustion gas from said combustion flues at intervals along the length of the sole flue, each of said sole flues having at one end an opening adapted to be used alternately for exhaustion of combustion gas and, on reversal of the oven, for admission of air, the effective areas of the passages from the sole flues through the combustion flues along each flue wall being regulated in size to correspond with the width of the coking chamber from end to end, said oven having also gas ports leading to said combustion flues and graduated in proportion to the width of the coking chambers.

3. A coke oven having coking chambers which are wider at one side than at the other side of the oven with flue walls between them and having in each flue wall a line of valveless combustion flues and having for each flue wall a pair of regenerators, a pair of sole flues for supplying air to and taking combustion gas from said combustion flues at intervals along the length of each sole flue, said sole flues having at one end a single opening adapted to be used alternately for exhaustion of combustion gas and, on reversal of the oven, for admission of air and having openings between the sole flues and the combustion flues along each flue wall graduated in size continuously from one side of the oven to the other, the wider openings being at the same side of the oven as the wider portion of the coking chambers.

4. A coke oven having coking chambers which are wider at one side than at the other side of the oven with flue walls between them and having in each flue wall a line of combustion flues and a pair of sole flues for supplying air to and taking combustion gas from said combustion flues at intervals along the length of each sole flue, said sole flues having at one end a single opening adapted to be used alternately for exhaustion of combustion gas and, on reversal of the oven, for admission of air and having passages from the sole flues to the combustion flues along each flue wall, the effective areas of which passages are graduated in size continuously from one side of the oven to the other, the greater areas being at the same side of the oven as the wider portion of the coking chambers, in combination with regenerator chambers one for each sole flue and commu- 125

nicating with the latter at said one end thereof.

5. A coke oven having coking chambers with flue walls between them and having in each flue wall a line of combustion flues and having sole flues for supplying air to and taking combustion gas from said combustion flues at intervals along the length of each sole flue, there being two sole flues arranged end to end for each flue wall, the effective areas of the passages from each end-to-end pair of sole flues through the combustion flues of the corresponding flue wall being graduated in size continuously 10 from one side of the oven to the other.

6. A coke oven having coking chambers with flue walls between them and having in each flue wall a line of combustion flues and having sole flues for supplying air to and taking combustion gas from said combustion flues at intervals along the length of each sole flue, there being two sole flues arranged end to end for each flue wall, the effective areas of the passages from each end-to-end pair of

sole flues through the combustion flues of the corresponding flue wall being graduated in size continuously from one side of the oven to the other, each end-to-end pair of flues serving as admission flues while the adjacent pairs serve as exhaust flues. 25

7. A coke oven having coking chambers with flue walls between them and having in each flue wall a line of combustion flues and having sole flues for supplying air to and taking combustion gas from said combustion flues at intervals along the length of each sole flue, the tuyères for the entrance of air at one end of a combustion flue from one of said sole flues and for the exit of products of combustion at its other end into another of said sole flues being graduated continuously from one end of the coking chamber or retort to the other in proportion to the width of the retort. 30 35

In witness whereof, I have hereunto signed my name. 40 45

WILLIAM H. WRIGHT.
